WRINGER AND THE LIKE

Walter L. Kauffman, II, Erie, Pa., assignor to
 Lovell Manufacturing Company, Erie, Pa., a
 corporation of Pennsylvania

Application October 5, 1939, Serial No. 298,100

11 Claims. (Cl. 68—249)

Power wringers and the like are usually supplied with safety devices. Many of such wringers are provided with indexing mechanisms by which the device may be swung to different angles and be operative in each position.

Safety devices are of two general types, one releasing pressure from the mechanism, and the other disconnecting the drive mechanism. It is desirable to retain the indexing mechanism in locked position during the time the driving connection is acting, and it is also desirable ordinarily to lock the release mechanism while the wringer is in neutral with relation to the drive mechanism so that there will not be a release movement unless desired and when the driving mechanism is disconnected.

This mechanism is particularly desirable in connection with so-called instinctive releases, that is, releases operating in response to a movement of the wringer. The invention is intended to accomplish these desirable functions. Features and details of the invention will appear from the specification and claims.

A preferred embodiment of the invention is illustrated in the accompanying drawings as follows:

Fig. 1 shows a front elevation of a wringer partly in section.

Fig. 2 a section on the line 2—2 in Fig. 1.

Fig. 3 is a section on the line 3—3 in Fig. 1 showing the driving mechanism set at neutral.

Fig. 4 a similar view with the driving mechanism in driving position.

Fig. 5 a section on the line 5—5 in Fig. 1 with the driving mechanism set at neutral.

Fig. 6 a similar section with the driving mechanism set at driving position.

Fig. 7 a plan view looking from the bottom, of one end of the top bar.

Fig. 8 a similar view with the parts in release position.

Fig. 9 a section on the line 9—9 in Fig. 7.

Fig. 10 a section on the line 10—10 in Fig. 8.

Fig. 11 shows a top view of the control mechanism with the top of the case removed and with the wringer at central position and the driving connection set.

Fig. 12 a similar view with the wringer offset to a release position.

1 marks a base of a wringer frame, 2 and 2a stiles extending upwardly from the base, the parts as shown being of stamped metal and the stiles being hollow. 3 a top member or top bar of the frame. Rolls 4 and 5 are mounted in the frame. These rolls are provided with shafts 6 55

and 7 respectively. The lower shaft 6 extends into a pressure stop device which is adapted to stop the rolls when the pressure on the rolls is released.

5 This particular pressure stop forms no part of this invention, but is similar to that shown in Patent No. 2,123,850 issued to me July 12, 1938. This roll stop has an automatic clutching member 8, conical in shape, in which the shaft 6 is journaled and the end of this conical member has notches 9 adapted to receive pins 10 in the shaft 6. The conical surface of the member 8 is journaled in a bearing 11 mounted in one of the side stiles, the opposite end having the usual shaft bearing. The member 8 is hollow and has a spring 12 which tends to force it toward release position, and the conical surface, when pressure is exerted, moves the member 8 into engagement with the pin. In this way the roll drive is stopped automatically if the pressure is released.

The upper shaft 7 is journaled in bearings 13 which are slidingly mounted in the side stiles. A spring 14 rests on the bearings and an adjusting screw 15 is mounted in the top bar 3 and adjusts the pressure of the spring.

A reset lever 16 is pivotally secured at one end of the top bar 3. It is connected by a link 18 to the side stile, the link 18 being pivotally mounted at 19 to the side stile and at 20 to the reset lever. The pivots 17, 19 and 20 are slightly out of line so as to provide a stable position when the reset lever is in set position.

35 A release handle 21 is hinged on the reset lever and rests on an abutment 22 at the upper end of the lever so that when pressure is delivered downwardly on the lever 21, the reset lever is moved to unstable position to effect a release of the top bar, the hinge between the lever 21 and the reset lever permitting the continued movement of the reset lever to effect a release.

The end of the top bar at the driving end of the wringer is also provided with a release device. This includes a latch 23 which has side flanges 23a and a connecting plate 23b. The flanges 23a have V-shaped slots 24, and the latch is pivoted on a pin 25 which extends through the sides of the top bar and through the slots 24. The latch has a shoulder 26 which engages an upper wall 27 of a notch 28 in the side stile so that when the latch is locked in position, the top is locked with the stile.

45 A spring 29 is provided on a loose pin 30 between the top bar and the latch and yieldingly swings the latch into set position. The latch has a release finger 23c at its inner end and this is

engaged by a return bend 31 on a release lever 32. The release lever is pivoted on a screw 33, the screw extending into the top bar. The outer end of the latch lever extends through the end of the top bar and has a downwardly extending engaging portion 34 by which the latch lever is operated in a manner hereinafter described.

A gear head 35 has a swivel extension 36 which is journaled in a top 37 of the usual post on which the wringer is mounted. The wringer is supported from the gear head by means of links 38, these links being pivotally secured to the gear head by pins 39 which extend through the top and bottom links and the inner ends of these links are secured to the wringer by pins 40 which extend through the links and through flanges 41 on a mounting plate 42.

The member 8 extends into a coupling sleeve 43 which is provided with slots 44 receiving pins 45 on the member 8. Pins 46 engage the opposite end of the sleeve 43, these pins extending through a shaft 47. The shaft 47 is journaled in bearings 48 in the head, and reversing gears 49 are opposingly mounted and locked with the shaft. The gears have clutch detents 50 on their inner faces adapted to engage clutch jaws 51 on a clutch block 52. The clutch block has the usual groove which is engaged by an eccentric pin 53 mounted on a shaft 54.

The shaft 54 is journaled in a bearing 55 in the head. The shaft has an extension 54a which extends through a case 56 which is fixed with relation to the head. The upper end of the extension 54a has a reversing or operating handle 57.

By operating the handle and turning the shaft 54, the eccentric pin operating in the groove moves the block from one reverse gear toward the other or places it between the gears or in neutral so that neither gear is driven. The gears 49 mesh with a gear 49a which is fixed on the upper end of a vertical drive shaft 49b and are driven from some source of power, usually the same power as drives the washing machine with which the wringer is associated.

A lever 58 is pivotally mounted by a screw 59 on the head 35. It is provided with a slot 60 in which operates an eccentric 61 carried by the shaft 54a so that as the handle 57 is swung from driving position to neutral, the lever 58 is swung, having a neutral position at the center and driving positions at each side of the center, one driving position being shown in Fig. 4. The lever extends outwardly within the case and is provided with a downwardly extending end 62, the lower end of which has a slot 63, the slot 63 registering with an upwardly extending end 64 of a detent and index lever 65 when the lever 58 is in neutral. The detent and index lever is pivoted on a pin 66 secured in the head and has a forwardly extending finger 67 which engages index notches 68 in the upper end of the post 37.

A plate 69 having slots 70 is secured to the under side of the top of the case 56 by screws 71, the plate in this way being slidingly mounted on the case. The outer end of the plate is in position to be engaged by a cam 72 mounted on the extension 54a.

When the shaft 54 is in neutral the cam 72 is centered in the position shown in Fig. 2 and has moved the plate inwardly. The inner end of the plate 69 has a notch 73, an end 74 of the notch extending over the sides of the stile 2a, thus locking the wringer against forward or back movement with relation to the head. A spring

75 anchored at 76 on the plate 69 and on a pin 77 secured to the top of the case 56 yieldingly withdraws the plate so as to disengage the ends 74 from the stile. The plate is provided with a slot 78 to accommodate this movement of the plate.

5 The end 34 of the lever 32 extends through a notch 34a in the top of the case 56 so that if the wringer is pulled or pushed from its central position, the lever 32 is swung to carry the end 31 off the finger 23c and allow the latch to release the top bar. By locking the wringer frame against such movement, the instinctive release, as it is called, that is a release responsive to a movement of the wringer frame, is locked.

10 15 In the operation of the device, when the wringer is in neutral, that is to say the rolls are stationary, the index lever may be operated so as to release the wringer and the wringer swung to the desired operation and the index lever returned, locking it in that position. The pressure on the top bar is set through the reset lever and the screw, as desired, ordinarily merely the 20 operation of the reset lever.

15 When it is desired to operate the wringer, the handle 57 is operated, throwing the driving 25 mechanism into operation in either direction desired. As the handle 57 is swung to start the driving connection, the lever 58 is swung, carrying the slot 63 out of register with the end 64 so that during the driving operation the indexing 30 device is locked. It will be apparent that the means for locking the index against release with the wringer drive in driving relation has contact with a vertical surface of the index device.

35 On the other hand, the swinging of the handle 57 and consequently the cam 72 has permitted the withdrawal of the locking plate 69 so that the wringer is free to move forward or back in response to a pull or push on the wringer so that 40 the top bar may be released by such movement so as to relieve the pressure (see Figs. 11 and 12). If the pressure is released thus by the instinctive action, the pressure is not only taken off the rolls, but through the stop mechanism including the member 8, the drive connection to the rolls 45 is broken so that the rolls stop.

What I claim as new is:

1. In a wringer or the like having a frame; rolls mounted in the frame; pressure means for the rolls; a driving head on which the frame is mounted; a release device for relieving pressure on the rolls; reversing gears driving the rolls; and means controlling the gears having neutral and driving positions; the combination with the means controlling the gears and the release device of devices locking the release device against release action whenever the wringer drive is in neutral.

2. In a wringer or the like having a frame; rolls mounted in the frame; pressure means for the rolls; a driving head on which the frame is mounted; a release device for relieving pressure on the rolls; reversing gears driving the rolls; and means controlling the gears having neutral and driving positions; the combination with the means controlling the gears and the release device of devices locking the release device against release action whenever the wringer drive is in neutral; and an auxiliary pressure release for releasing the pressure.

3. In a wringer or the like having a frame; rolls mounted in the frame; pressure means for the rolls; a movable driving head on which the frame is swiveled; a release device for relieving pressure on the rolls responsive to a movement

of the frame; reversing gears driving the rolls; means controlling the gears having neutral and driving positions; and an index means for locking the head against movement; the combination with said means controlling the gears and the release device of devices locking the release device against release action whenever the wringer drive is in neutral; and devices locking the index means against action when the wringer is in driving relation.

4. In a wringer or the like having a frame comprising a detachable top bar; rolls mounted in the frame; pressure means for the rolls exerting pressure from the top bar; a driving head on which the frame is mounted; a release device for releasing the top bar to release pressure on the rolls; reversing gears driving the rolls; and means controlling the gears having neutral and driving positions; the combination with the means controlling the gears of devices locking the release device against release action whenever the wringer drive is in neutral.

5. In a wringer or the like having a frame; rolls mounted in the frame; a pressure means for the rolls; a movable driving head on which the frame is movably mounted; reversing gears driving the rolls; means controlling the gears having neutral and driving positions; and an index means for locking the head against movement; the combination with the means controlling the gears and the index means of an instinctive release device actuated by a relative movement of the frame and head; devices locking the instinctive release device against release action whenever the wringer drive is in neutral; and devices locking the index means against action when the wringer is in driving relation.

6. In a wringer or the like having a frame; rolls mounted in the frame; a pressure means for the rolls; a driving head; a paralleling connection between the head and the wringer permitting a movement of the wringer while maintaining the wringer in different positions parallel to a common plane; an instinctive release actuated by the relative movement of the frame and head through the paralleling connection; reversing gears driving the rolls; and means controlling the gears having neutral and driving positions; the combination with said paralleling connection, means controlling the gears and instinctive release of devices locking the instinctive release against action whenever the wringer drive is in neutral.

7. In a wringer or the like having a frame; rolls mounted in the frame; a pressure means for the rolls; a driving head; a paralleling connection between the head and the wringer permitting a movement of the wringer while maintaining the wringer in different positions parallel to a common plane; reversing gears driving the rolls; means controlling the gears having neutral and driving positions; and an index device controlling the position of the head; the combination with said means controlling the gear and the index device of an instinctive release actu-

ated by the relative movement of the frame and head through the paralleling connection and means having contact with a vertical surface of the index device for locking the index against release with the wringer drive in driving relation.

8. In a wringer or the like having a frame; rolls mounted in the frame; a pressure means for the rolls; a driving head; a paralleling connection between the head and the wringer permitting a movement of the wringer while maintaining the wringer in different positions parallel to a common plane; an instinctive release actuated by the relative movement of the frame and head through the paralleling connection; reversing gears driving the rolls; means controlling the gears having neutral and driving positions; and an index device controlling the position of the head; the combination with said instinctive release, means controlling the gears and the index device of devices locking the instinctive release against release action with the wringer drive in neutral; and means locking the index against release with the wringer drive in driving relation.

9. In a wringer or the like having a frame; rolls mounted in the frame; a pressure means for the rolls; a driving head on which the frame is swiveled; a release device for the pressure device; and reversing gears driving the rolls; the combination with the release device and reversing gear of means above the head for controlling the reversing gears comprising a control shaft putting the gears in neutral or in driving position; and devices locking the release device actuated from the control shaft against release action whenever the wringer drive is in neutral.

10. In a wringer or the like having a frame; rolls mounted in the frame; pressure means for the rolls; a driving head on which the frame is mounted; a release device actuated by a relative movement of the frame and head; reversing gears driving the rolls; and means controlling the gears having neutral and driving positions; the combination with the release device and means controlling the gears of means actuated by the controlling means locking the frame against movement relatively to the head.

11. In a wringer or the like having a frame; rolls mounted in the frame; pressure means for the rolls; an adjustable driving head on which the frame is mounted; reversing gears driving the rolls; means controlling the gears having neutral and driving positions; means actuated by the controlling means locking the frame against movement relatively to the head; and an indexing device locking the head as adjusted; the combination with the controlling means and indexing device of a release device actuated by a relative movement of the frame and head, and locking means actuated by the controlling means locking the index device against release with the driving connection in driving relation.

WALTER L. KAUFFMAN, II.
